UNITED STATES PATENT OFFICE

JOHN C. STOKES, OF HOUSTON, TEXAS, ASSIGNOR TO REED ROLLER BIT COMPANY, OF HOUSTON, TEXAS, A CORPORATION OF TEXAS

ROLLER BIT

Application filed September 6, 1927. Serial No. 217,675.

This invention relates to deep well drilling apparatus and more particularly to roller bits.

Its object is the provision of a roller bit embodying new and improved means to drive, support and clean the roller cutters thereof.

In the accompanying drawings, which are illustrative of the preferred embodiments of the invention, Fig. 1 is a side elevation; Fig. 2, a partly sectional elevation; Fig. 3, a bottom plan view; Fig. 4, a section on the line 4-4 of Fig. 2; and Fig. 5, a partly sectional elevation of a modification.

Referring more specifically to Figs. 1, 2, 3 and 4, the bit head comprises a main section 1, adapted to be attached to a drill pipe (not shown), and a longitudinally divisible cutter section 2. The lower ends 3 of the two parts of which the cutter section 2 is made are beveled to define a recess in the bottom of the head. Substantially frusto-conical cutters 4 are rotatably mounted on spindles which project downwardly and inwardly from the ends 3.

The main section 1 has a reduced extension 5 fitting in the cutter section, the meeting faces of the two parts of the cutter section being recessed for the reception thereof. Reduced extension 5 has an annular groove 5^a therein, bolts 6, which hold the two parts of the cutter section together, resting in said groove to rotatably lock the cutter section on said extension. Removable bushings 7 may be interposed between the meeting faces of the two sections; and additional bolts 8 may be used to lock the two parts of the cutter section 2 together.

In deep well drilling operations, the weight of the drill pipe is so great, and a bit is subjected to such strains, that it is most difficult to provide supports strong enough to hold the roller cutters firmly and immovably in the head.

And in roller bits of this general type, that is, bits embodying a head having oppositely disposed depending walls from which the cutter spindles project, it has been impossible, from a practical standpoint, to make said walls sufficiently strong to properly support the cutters under the most trying conditions,

and at the same time preserve substantially the size and design of the head. The said walls are accordingly bent inwardly when the cutters of a bit attached to a heavy string of pipe have been subjected to impact.

This invention provides means to positively support the cutters without impairing the cutting action thereof. The means referred to is shown as a beveled or substantially frusto-conical gear 9 non-rotatably locked on the lower end of extension 5, and having teeth meshing with the teeth of the cutters 4.

The head is provided with a central water course 11 extending through extension 5, branch water courses 12 communicating with annular chamber 13, and outlets 14. The gear 9 has an opening 9^a to permit the discharge of water between the cutters 4 and directly upon the bottom of the hole. The outlets 14 are four in number and are so arranged that water will be thereby discharged upon those teeth of the cutters and gear immediately adjacent the engaged teeth thereof.

Suitable shields 15 may be used to confine the flow of the cleaning water and thus increase the velocity thereof, and to prevent the entry between the cutters and gear of large stones and the like.

When the head 1 and its integral extension 5 and gear 9 locked thereon are rotated and the cutters 4 are in contact with the bottom of the hole, the gear 9 rolls the cutters around the bottom of the hole, the cutter section 2 rotating on the extension 5. The outlets 14 disposed back of the engaged teeth of the gear and cutters will discharge cleaning water upon the teeth about to become engaged; and the outlets 14 in front of the engaged teeth will discharge cleaning water upon the teeth which have just been disengaged. As shown clearly in Figs. 2 and 3, the outlets 14 discharge water upon the cutting teeth in a direction longitudinal of said teeth, and, therefore, down the valleys thereof.

Thus the teeth of the cutters are subjected successively to the initial cleaning water, the cleaning gear teeth, and to the ultimate cleaning water.

In the modification illustrated by Fig. 5,

the head 16 has a centrally disposed recess 16^a, in which gear 17 is rotatable. The gear may be held in place by cutters 18, and provided with ball bearings 19. The water courses shown correspond to those of Figs. 1, 2, 3 and 4, hereinabove described.

In the form shown by Figs. 1, 2, 3 and 4, the gear 9 is the driving element and the cutters 4 the driven. In the modification of 10 which Fig. 5 is illustrative, the gear 17 is not the driving element but, instead, the driven. It may be properly referred to as an idler gear. It provides substantially the same support for the cutters 18, it cleans said cutters in substantially the same manner, and it insures equal rotation of said cutters. This 15 modification is particularly advantageous because of the housing within the head of the gear 17 and its bearings 19.

A single piece cutter section may be substituted for the longitudinally divisible cutter section 2 shown in Figs. 1, 2, 3 and 4, and means provided whereby the cutters 4 may be laterally slidable into and out of the recess 25 in the bottom thereof.

Various other changes will be apparent to those skilled in the art, and the hereinafter appearing claims are not limited in scope to the specific embodiments shown.

30 I claim:

1. In a drill, a substantially conical roller cutter having longitudinal cutting teeth and a substantially conical support, said support being rotatable with respect to said cutter and having teeth meshing with the cutting teeth of said cutter.

2. In a drill, a head, oppositely disposed substantially conical roller cutters on said head, said cutters having cutting teeth, and a 40 substantially conical support between said cutters, said support being rotatable with respect to said cutters and having teeth meshing with the teeth of said cutters.

3. In a drill, a head, oppositely disposed spindles on said head, said spindles projecting downwardly and inwardly, substantially conical roller cutters on said spindles, said cutters having cutting teeth, and a beveled gear between said cutters and having teeth meshing with the teeth of said cutters.

4. In a drill, a head having a main section and a cutter section, roller cutters on said cutter section, said cutters having cutting teeth, and a gear on said main section, said 55 gear having teeth meshing with the teeth of said cutters.

5. In a drill, a head, a roller cutter on said head, said cutter having cutting teeth, and a support for said cutter, said support having 60 teeth meshing with the teeth of said cutter, and said head having a water course to discharge water upon said cutter adjacent the engaged teeth of said cutter and support.

6. In a drill, a head, a roller cutter on said head, said cutter having cutting teeth, and

a support for said cutter, said support having teeth meshing with the teeth of said cutter, and said head having a water course to discharge water upon said cutter adjacent the engaged teeth of said cutter and support, and in a direction longitudinally of the teeth of said cutter.

7. In a bit of the class described, the combination of: a body adapted to be secured to a drill pipe, said body being provided with driving teeth; a cutter support rotatable on said body; and a cutter retained by said cutter support and being provided with cutting teeth, said driving teeth on said body being engaged with said cutting teeth on said cutter.

8. In a drill bit, the combination of: a body adapted to be secured to a drill pipe, said body being provided with driving gear teeth; a cutter support rotatable on said body; and a cutter retained by said cutter support and being provided with cutting teeth, said cutting teeth engaging the said driving teeth on said body.

JOHN C. STOKES.
